UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION.

SELF-OPENING DIE HEAD.

Application filed June 25, 1924. Serial No. 722,277.

To all whom it may concern:

Be it known that I, ALBERT F. BREITENSTEIN, a citizen of the United States, residing at New Haven, in the county of New Haven and State of Connecticut, have invented a new and useful Improvement in Self-Opening Die Heads; and I do hereby declare the following, when taken in connection with the accompanying drawings and the characters of reference marked thereon, to be a full, clear, and exact description of the same, and which said drawings constitute part of this application, and represent, in—

Fig. 1 a view in front elevation of a self-opening die-head constructed in accordance with my invention.

Fig. 2 a view thereof in longitudinal central section.

Fig. 3 a view thereof in transverse section on the line 3—3 of Fig. 2.

Fig. 4 a view in front elevation of the die-body stripped.

Fig. 5 a broken, sectional view on the line 5—5 of Fig. 1.

Fig. 6 a similar view on the line 6—6 of Fig. 1.

Fig. 7 a detached, perspective view of the tripping-member.

Fig. 8 a detached, perspective view of the locking-segment.

Fig. 9 a corresponding view of the complementary filler-segment.

My invention relates to an improvement in self-opening die-heads, whether rotary or stationary, the object being to provide the same with simple, effective and durable means for locking and tripping the chasers.

With these ends in view, my invention consists in a self-opening die-head characterized by having a radially-movable locking-segment mounted in its adjusting-ring in position to be moved outward into engagement with an abutment in the operating-sleeve, means for so moving the said segment, and a tripping-member mounted in the operating-sleeve and co-acting with the said locking-segment for forcing the same inward, out of engagement with the said abutment of the sleeve, the said tripping-member having a projection beyond the periphery of the sleeve, whereby it is engaged for operation by a suitably arranged stop.

My invention further consists in a self-

opening die-head having certain details of construction as will be hereinafter described and particularly recited in the claims.

In carrying out my invention, as herein shown, I employ a pivotal tripping-member 10 located in a radial slot 11 in the operating-sleeve 12 of the die-head. At its inner end, the said member 10 is formed with a transverse hole 13 receiving a pin 14 on which the member has swinging movement and which is mounted in the said sleeve. The outer end of the said member is formed with a limiting-opening 15 receiving a stoppin 16, also mounted in the sleeve, and of smaller diameter than the diameter of the said opening, whereby the swinging movement of the said member is limited. Upon the curved outer edge of its outer end the said member is formed with a curved tripping-lug 17, designed to co-act with a suitable stop properly located in the machine in the ordinary manner and not shown herein. The curved inner edge of the said member rides upon and co-acts directly with the correspondingly-curved periphery of a radially-movable locking-segment 18 located in a circumferential groove 19 in the adjusting-ring 20 of the die-head, the said ring being internally threaded, as usual (Fig. 2), for being screwed upon the threaded portion of the tubular shank 21 of the skeleton die-head body 22. Diametrically opposite the locking-segment 18 and in the same groove 19 I locate a complementary filler-segment 23 having neither radial nor endwise movement with reference to the adjusting-ring 20 in which it is mounted. At its ends the said filler-segment is formed with slots 24 receiving helical springs 25 respectively abutting against the ends of the locking-segment 18 and exerting a constant effort to move the same radially outward for the engagement of its forward outer edge with an abutment-shoulder 26 forming the forward wall of an eccentric groove 27 leading out of the bore 28 of the operating-sleeve 12. The eccentric character of the locking-groove 27 is clearly shown in Fig. 3.

To prevent the endwise displacement of the filler-segment 23 in the groove 19, it is provided with a key 29 fastened by a rivet 30, and projecting into a keyway 31 in the sleeve 12. The filler-segment 23 is also provided in its external periphery with a transverse clearance groove 32 (Fig. 9) for the

clearance of the stud-like inner end 33 of a stop-screw 34 (Figs. 2 and 3) mounted in the ring 12 for limiting the movement of the operating-sleeve 12 in both directions 5 upon the adjusting-ring 20.

To prevent the relative rotation of the operating-sleeve 12 and the skeleton die-head body 22, the said sleeve is provided at opposite points in its forward face with two

10 guide-pins 35 (Figs. 4 and 6) entering corresponding holes 36 in the body 22, the said pins reciprocating back and forth in the holes 36, as the sleeve is moved back and forth in the operation of the device.

15 For the self-opening action of the die-head, I employ two helical springs 37 (Figs. 4 and 5) located opposite each other and extending at their opposite ends into deep bores 38 in the operating-sleeve and complementary bores 39 in the body 22.

As herein shown, my improved die-head is provided with four equidistant chasers 40 retained in place by four segmental plates 41 secured to the forward face of the body 25 22 by rivets 42. Spring-actuated plungers 43 exert a constant effort to move the chasers outward into engagement with the bevelled inner edge of the outer end of the sleeve 12 as shown in Fig. 2. But the specific character 30 of the chasers and the mode of mounting and operating them has nothing to do with my present invention, being made the subject-matter of a co-pending application, filed by me in even date herewith. So far 35 as my improved tripping-member is concerned, it may be used in self-opening die-heads furnished with chasers of different construction, mode of mounting and operation.

40 As shown herein, my improved self-opening die-head is in its closed position ready for a threading operation, at which time the locking-segment 18 is pushed outward into the eccentric groove 27 in the sleeve 45 12, in which position its forward edge contacts with the forward wall 26 of the said groove, whereby the sleeve is locked in its forward position, in which it holds the chasers 40 in their cutting positions against the tension of their spring-actuated plungers, and the sleeve 12 against the action of the helical springs 37, the said plungers tending to move the chasers outward and the said springs tending to move the sleeve 55 rearward.

At a predetermined point in the threading operation, the lug 17 of the tripping-member 10 is brought into contact with an adjustable stop or abutment, set in the usual 60 and well known manner, according to the character of the work to be done. When this engagement takes place, the tripping-member 10 is forced inward, rocking on the pin 14, whereby the locking-segment is forced inward against the tension of the

springs 25 from its eccentric locking-position into its concentric releasing-position, in which latter it is cleared from engagement with the abutment-shoulder 26 in the sleeve, which is now released to the action of the 70 opening-springs 31, whereupon the sleeve is moved rearward and the cutters released for being moved radially outward by the action of their spring-actuated plungers.

To permit the sleeve 12 to move forward 75 from its tripped to its chaser-closing position, the locking-segment 18 is formed with a peripheral bevel 44 (Figs. 2 and 8), which is engaged in the outward movement of the sleeve at the point 45 thereof, whereby the 80 segment is cammed inward and the sleeve allowed to ride over it until the segmental groove 26 is brought into line with the segment, which is then lifted into its locked position, as shown in Fig. 2, by the springs 85 25.

As already explained, my improved tripping-device is not limited to use with the chasers herein shown and described, since it may be embodied in self-opening die-heads 90 having other forms of chasers and means for mounting the same; nor do I limit myself to the exact tripping-device herein shown and described, since the same may be modified in details of construction to meet 95 a variety of conditions of use. I would, therefore, have it understood that I do not limit myself to the exact tripping-mechanism shown and described but hold myself at liberty to make such departures therefrom 100 as fairly fall within the spirit and scope of my invention.

I claim:

1. In a self-opening die-head, the combination with the body thereof, of an adjusting-ring threaded upon the said body, an operating-sleeve having sliding axial movement with respect to the said body and having upon its inner face a semi-circular, eccentric locking-abutment, a radially-movable locking-segment carried by the said adjusting-ring in position for engagement with the said abutment of the sleeve, yielding means for moving the said locking-segment bodily outward into engagement with the said abutment, and a tripping-member mounted in the operating-sleeve in position to be externally-operated and adapted to engage with the said locking-segment for forcing the same bodily inward from its eccentric locking-position in which it engages with the said eccentric locking-abutment, into its concentric releasing-position in which latter it clears the said abutment. 115

2. In a self-opening die-head, the combination with the body thereof, of an adjusting-ring threaded upon the said body and having a peripheral annular groove, an operating-sleeve having sliding axial movement with respect to the said body and hav- 125 130

ing upon its inner face a semi-circular eccentric locking-abutment, a radially-movable locking-segment located in the said groove in position for engagement with the 5 said abutment of the sleeve, a complementary filler-segment located in the said groove in opposition to the said locking-segment therein, springs interposed between the adjacent ends of the said segments for moving the 10 said locking-segment bodily outward into its eccentric locking-position, and a tripping-member mounted in the sleeve in position to be externally operated and adapted to engage, when forced inward, 15 with the locking-segment for forcing the same bodily inward from its eccentric locking-position into its concentric releasing-position, in which latter it clears the said abutment.

20 3. In a self-opening die-head, the combination with the body thereof, of an adjusting-ring threaded directly upon the said body and having an annular peripheral groove, an operating-sleeve having bearing 25 upon the said ring and body and formed with an eccentric locking-groove leading out of its bore, a radially-movable locking-segment located in the groove in the said ring, a complementary filler-segment located in the 30 said groove in opposition to the said locking-segment, means for bodily moving the locking-segment radially into the eccentric locking-groove leading out of the bore of the said sleeve, and a tripping-member located in a radial slot in the sleeve in 35 position to engage with the outer periphery of the locking-segment for forcing the same bodily inward against the action of the said means, from its eccentric locking-position 40 into its concentric releasing-position, in which latter it clears the said abutment.

45 4. In a self-opening die-head, the combination with the body thereof, of an adjusting-ring threaded upon the said body and having an annular peripheral groove,

an operating-sleeve having sliding axial movement with respect to the said body, a radially-movable locking-segment located in the said groove in the said ring, a filler-segment located in the said groove in opposition to the said locking-segment, springs 50 interposed between the adjacent ends of the segments for moving the locking-segment bodily outward into position for engagement with the sleeve for locking the same in 55 its closed position, and a tripping-member pivotally mounted in the said sleeve in position to engage with the said locking-segment for forcing the same bodily inward for unlocking the sleeve, the said tripping-member 60 projecting from the periphery of the sleeve in position to be engaged for its operation.

5. In a self-opening die-head, the combination with the body thereof, of an adjusting-ring threaded thereupon, an operating-sleeve having sliding axial movement with respect to the said body and provided upon its inner face with a semi-circular eccentric locking-abutment, a radially-movable locking-segment carried by the said adjusting-ring in position for engagement with the said abutment of the sleeve, and formed with a cam-surface upon its outer face, yielding means for moving the said locking-segment into engagement with the said 65 abutment, and a tripping-member mounted in the operating-sleeve in position to be externally operated and adapted to engage with the said locking-segment for forcing the same bodily inward from its eccentric locking-position, in which it engages with the said eccentric locking-abutment, into its 70 concentric releasing-position, in which latter it clears the said abutment, the said cam-surface of the locking-segment being engaged by the operating-sleeve to permit the 75 die-head to be re-set.

In testimony whereof, I have signed this specification.

ALBERT F. BREITENSTEIN.
